UNITED STATES PATENT OFFICE.

WILLIAM M. DUNCAN, OF ALTON, ILLINOIS.

ADJUSTABLE HAMMER FOR DISINTEGRATORS AND THE LIKE.

Application filed August 1, 1927. Serial No. 209,747.

This invention relates to adjustable hammers for disintegrators and the like. Hammers of this kind are pivoted to a rotary carrier, and the device herein shown permits them to be adjusted toward and away from the axis of the rotary carrier, so as to obtain the desired clearance between the hammers and the surface which supports the material to be crushed or pulverized. This adjustment enables the hammers to most effectively perform their function for a long period of time, after the free ends, or heads, of the hammers are worn by contact with the material in the apparatus.

The hammers are subjected to extremely severe shocks and one of my objects is to produce a strong and durable adjusting device adapted to withstand such shocks without danger of breakage or displacement.

A further object is to produce a simple and inexpensive adjusting device which can be easily and quickly manipulated to vary the positions of the hammers.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is a fragmentary view showing a series of hammers adjustably secured to a rotary carrier.

Fig. 2 is a view partly in elevation and partly in section on the line 2-2 in Fig. 1.

Fig. 3 is a perspective view of one of the adjustable blocks.

To illustrate one form of the invention, I have shown a rotary carrier comprising two pairs of disks 1 secured to a rotary shaft 2, so as to rotate with the shaft. The disks of each pair may be located between smaller disks 3 and at opposite sides of a spacing disk 4. Fastening devices, such as rivets 6 may be used to connect the several disks in each group.

The hammer may be of any desired shape. I have shown substantially U-shaped hammers, each comprising a head 7 with arms 8 extending from its ends. The object of the

adjustment hereinafter described is to maintain the desired clearance between the heads

7 and the grinding surface 9 which supports the material to be crushed or pulverized.

One end of each arm 8 is confined between a pair of disks 1, and a pivot rod 10 passes through both pairs of disks and also through the arms 8. Polygonal blocks 11 are pivotally mounted on the pivot rod 10, each block being surrounded by and interlocked with one of the arms 8. The disks 1 prevent lateral displacement of the blocks 11 and the arms 8 thereby retaining the blocks in interlocking engagement with the arms.

Each arm 8 has an opening conforming to the outer edge of its polygonal block 11, and said block is eccentric to the pivot rod 10 on which it is mounted. The blocks are adapted to occupy different positions in the arms 8 so as to locate the hammers in different positions with respect to the grinding surface 9.

To adjust the hammers, the pivot rods 10 are removed from the disks 1, and the arms 8 are withdrawn from the disks. The blocks 11 can be removed from the arms and replaced in any desired position to obtain the most satisfactory clearance between the hammers and the grinding surface 9.

The means for detachably securing the pivot rod to the rotary carrier is a tube 12 surrounding the pivot rod and confined between pairs of disks 1. The ends of this tube engage the inner disks 1 to prevent longitudinal displacement of the tube, and the pivot rod is detachably secured to the tube by means of a cotter pin 13. The pivot rod is thus securely held when the apparatus is in service but said rod can be easily and quickly removed to permit adjustment of the blocks 11.

The service shocks do not tend to displace either the pivot rods or the adjustable blocks 11. The blocks are pivotally mounted on the rods 10 so as to turn with the hammers, and although these blocks are eccentric to the rods, the shocks do not tend to change the positions of the blocks relative to the hammers.

I claim:

1. In a disintegrator, a rotary carrier, a pivot carried by said carrier, a hammer support pivotally mounted on said pivot, and a hammer carried by said support, said support being adjustable to vary the position of the hammer relative to the axis of said pivot.

2. In a disintegrator, a rotary carrier, a pivot carried by said carrier, and a hammer

adapted to swing about the axis of said pivot, said hammer comprising an arm surrounding said pivot, and an adjustable member located between said arm and pivot to vary 5 the position of the hammer relative to said pivot.

3. In a disintegrator, a rotary carrier, a pivot carried by said carrier, and a hammer adapted to swing about the axis of said pivot, 10 said hammer comprising an arm surrounding said pivot, and an adjustable member located between said arm and pivot to vary the position of the hammer relative to said pivot, said adjustable member being pivotally supported on said pivot and movable with the 15 hammer when the latter is in service.

4. In a disintegrator, a rotary carrier, a pivot carried by said carrier, and a hammer adapted to swing about the axis of said pivot, 20 said hammer comprising an arm surrounding said pivot, and an adjustable member located between said arm and pivot to vary the position of the hammer relative to said pivot, said adjustable member being a polygonal 25 block pivotally mounted on said pivot and detachably interlocked with said arm.

5. In a disintegrator, a rotary carrier, a pivot carried by said carrier, a polygonal block pivotally mounted on said pivot, said 30 block being eccentric to said pivot, and a hammer carried by said block.

6. In a disintegrator, a rotary carrier, a pivot carried by said carrier, a polygonal block pivotally mounted on said pivot, said 35 block being eccentric to said pivot, and a hammer carried by said block, said hammer

having an opening conforming to said polygonal block, and said block being adjustable to different positions in said opening.

7. In a disintegrator, a rotary carrier 40 comprising a pair of disks, a pivot rod extending through said disks, a polygonal block confined between said disks and pivotally mounted on said rod, and a hammer comprising an arm mounted on said block, said arm having an opening conforming to the outer edge of said polygonal block, said block being eccentric to said pivot rod, and the pivot rod being detachable from said carrier to permit removal of said block from 45 said opening.

8. In a disintegrator, a rotary carrier comprising two pairs of disks, an approximately U-shaped hammer provided with a pair of arms, each arm being confined between the disks of one of said pairs, a pivot rod passing through both pairs of disks and also through said arms, a pair of polygonal blocks pivotally mounted on said pivot rod and surrounded by the respective arms, said blocks being eccentric to said pivot, each arm having an opening conforming to its polygonal block and the block being adjustable to different positions in said opening, a tube surrounding said pivot rod and confined between said pairs of disks, and means whereby said tube is detachably secured to said rod to detachably secure said blocks and hammer.

In testimony that I claim the foregoing 70 I hereunto affix my signature.

WILLIAM M. DUNCAN.
